UNITED STATES PATENT OFFICE.

LAWRENCE E. HOFFMAN AND WILLIAM D. SCOTT, JR., OF HELENA, MONTANA.

RAILWAY-TIE.

1,186,903.

Specification of Letters Patent. Patented June 13, 1916.

Application filed March 18, 1916. Serial No. 85,144.

To all whom it may concern:

Be it known that we, LAWRENCE E. HOFFMAN and WILLIAM D. SCOTT, Jr., citizens of the United States, residing at Helena, in the 5 county of Lewis and Clark, State of Montana, have invented a new and useful Railway-Tie, of which the following is a specification:

This invention relates to metallic railway 10 ties, one of its objects being to provide a tie having a yieldingly supported top section on which the rails are adapted to be secured, the means employed for supporting the top section being housed within the tie and being 15 simple, durable and efficient.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, can be made within the scope of what is claimed, without 25 departing from the spirit of the invention.

In the accompanying drawings the preferred form of the invention has been shown.

In said drawings:—Figure 1 is a view partly in elevation and partly in longitudinal 30 section of a tie embodying the present improvements, rails being shown secured thereon. Fig. 2 is a horizontal section. Fig. 3 is a section on line A—B Fig. 1, said section being on an enlarged scale. Fig. 4 is a 35 perspective view of one of the supporting levers used in the tie.

Referring to the figures by characters of reference 1 designates a box-like member constituting the base of the tie, the same being 40 extended into an inverted box-like top member 2 capable of shifting upwardly and downwardly relative to the base. Bearing extensions 3 are provided within the base 1 and are engaged by trunnions 4 extending 45 from levers 5 the long arms of which are formed with recessed ends 6 which straddle a stem 7. This stem projects through an opening 8 in the base 1 and is provided at its lower end with a head 9 adapted to reciprocate within a housing 10 secured to 50 and depending from the base 1. Springs 11 are arranged within the housing and about the stem 7, these springs bearing at one end against the base 1 and at their other ends 55 against the head 9. The upper end of the stem is secured to a saddle 12 which strad-

dles the recessed ends of levers 5. The outer or short arm of each lever has a transverse groove 13 forming a seat for a rib 14 depending from the top section 2. One of 60 these ribs is provided for each lever and the two ribs are located directly under the rails R supported by the tie.

Formed upon the cover section 2 are retaining flanges 15 which overhang transverse grooves 16 formed in the top of the section 2. In these grooves are seated wedging blocks 17 which are overhung by the flanges and have shoulders 18 designed to lap the inner base flanges of the rails R. 70 The outer base flanges of the rails are adapted to be secured in like manner by wedging blocks 19 engaging flanges 20.

It will be understood that the springs 11, by bearing downwardly on the head 9, hold 75 saddle 12 down on levers 5 so that they will yieldingly support the section 2 above section 1. When the tie is subjected to pressure, however, the ribs 14 will thrust downwardly upon the short arms of the levers 80 and cause the long arms to pull upwardly through the saddle 12, stem 7 and head 9 against the springs 11 which will operate as cushions and retard the descent of the top section. Thus it will be seen that while the 85 tie is made entirely of metal, it will provide the necessary resiliency.

It will be noted that all of the working parts are housed where the operation thereof will not be interfered with. 90

What is claimed is:—

1. A metallic railway tie including a box-like member constituting the base of the tie, an inverted box-like member slidable upwardly and downwardly on the first mentioned member and constituting the top section of the tie, means for securing rails to said top section, oppositely extending levers fulcrumed within the first mentioned box-like member, spring controlled means engaging the inner end portions of the levers for retarding the downward movement of the outer end portions thereof, and depending portions upon the top section directly under the centers of the rails for thrusting downwardly upon the outer end portions of the levers. 100

2. A metallic railway tie including a box-like member constituting the base section of the tie, an inverted box-like member constituting the top section of the tie, said top section being slidable upwardly and down- 110

wardly upon the base section, means for fastening a rail to the top section, oppositely extending levers fulcrumed within the base section, said levers having outer short arms 5 and inner long arms, means depending from the top section and directly under the centers of the supported rails for engaging and thrusting downwardly upon the short arms of the respective levers, a housing depending 10 from the base section, a head slidably mounted in the housing, springs interposed between the head and the base section, a

stem extending from the head, and means carried by the stem for engaging the long arms of the levers.

15

In testimony that we claim the foregoing as our own, we have hereto affixed our signatures in the presence of two witnesses.

LAWRENCE E. HOFFMAN.
WILLIAM D. SCOTT, JR.
